Primary Examiner — Jae Liang(74) *Attorney, Agent, or Firm* — Morris O'Bryant Compagni Cannon, PLLC(57) **CLAIM**

The ornamental design for a flask with attached tumblers, as shown and described.

DESCRIPTION

FIG. 1 is a front side perspective view of a flask with attached tumblers showing our new design;

FIG. 2 is a front side view thereof;

FIG. 3 is a back side view thereof;

FIG. 4 is a top side view thereof; and,

FIG. 5 is a bottom side view thereof.

The broken lines in the drawings depict portions of the flask with attached tumblers that form no part of the claimed design.
